UNITED STATES PATENT OFFICE.

CHARLES L. GLAFCKE, OF MICHIGAN CITY, INDIANA.

FILING-CASE.

965,177.

Specification of Letters Patent. Patented July 26, 1910.

Application filed January 31, 1910. Serial No. 541,056.

To all whom it may concern:

Be it known that I, CHARLES L. GLAFCKE, a citizen of the United States, residing at Michigan City, county of Laporte, and State of Indiana, have invented certain new and useful Improvements in Filing-Cases, of which the following is a specification.

My invention relates to improvements in filing cases, the object of the invention being the production of a filing case adapted for business purposes which shall be simple of construction and convenient in use.

A further object of the invention is to provide means whereby the case may be increased in size to meet the demands of a growing business in order that the initial expenditure may be reduced to a minimum.

Other objects will appear hereinafter.

With these objects in view my invention consists in the novel construction and arrangement of parts which will be hereinafter fully described and particularly pointed out in the appended claims.

My invention further consists in a modification in the filing receptacles used in the device.

My invention will be best understood by reference to the accompanying drawings forming a part of this specification, and in which,

Figure 1 is a front elevation of my improved filing case in its preferred form, Fig. 2 is a transverse section taken on line $x-x$ of Fig. 1, Fig. 3 is a transverse section taken on line $y-y$ of Fig. 1, Fig. 4 is a perspective view of partitions used in the device, Fig. 5 is a perspective view of a filing receptacle supporting tray, Fig. 6 is a perspective view of a filing receptacle, Fig. 7 is a vertical longitudinal section of said filing receptacle, Fig. 8 is a perspective view showing the modified form of filing receptacle, and Fig. 9 is a longitudinal section of the latter.

Referring now to the drawings 1 designates the bottom of the filing case which is preferably of wood and rectangular in form, and 2 the top of the filing case which is similar to the bottom thereof. 3 designates 50 ends of the case which are only essential to render the device neater in appearance. Detachable slotted partitions 4 and 5 are provided which are adapted to support and separate the filing receptacles which will be 55 described hereinafter. The partitions 4 and

5 are provided with side and end portions, the former being provided with recesses 6, as clearly shown in Fig. 4. In order to secure the partitions 4 and 5 together and to properly position the same between the bottom and top portions 1 and 2 respectively bolts 7 are provided which pass through the recesses 6 and said top and bottom of the case and when the nuts of said bolts are tightened the partitions are firmly secured 65 in place. The filing receptacle trays 8 are substantially rectangular in form and are provided with side portions 9 which have downwardly extending flanges adapted to engage the slots 10 of the partitions 4 and 5. 70 These trays are removable in order that the case may be increased or decreased in size as desired.

Each filing receptacle 11 comprises a sheet metal rectangular box having a hinged lid 75 12 the size of the same being approximately equal to the size of the filing receptacle tray 8 so as to be capable of sliding on the latter. The lid 12 is hinged to the receptacle by means of a rod 13 having a bent arm 14 at 80 one end thereof the hinged joint being formed by means of extensions 15 provided on said lid. The arm 14 is provided to automatically open the lid 12 when the receptacle is nearly withdrawn from the case, 85 and in order to do this the end of said arm contacts with an end of a partition. This obviously causes the arm to rotate and to lift the lid 12, the latter closing by gravity when the receptacle is moved into the case. 90 The inside of each lid 12 is provided with card-holding members 16 and 16', and the card 17 inserted therein may have the addresses or other information regarding parties whose letters or other business papers 95 are contained in the receptacle.

In the modified form of receptacle supplementary lids 18 are provided and hinged to sides of the receptacle at right angles to the rear thereof by means of the rods 19. Said 100 rods are suitably pivoted and provided with radial arms 19' by means of which said lids may be manually opened or closed as desired. The lids 18 are also provided with card-holding members similar to those provided on the lid 12 and which may contain similar information when the business papers of two or more parties are filed in the receptacle. Each filing receptacle 11 is provided with a number card as shown in 110

Fig. 1, and in order to hold said cards in position card-holding members 15' are provided.

While I have shown what I deem to be 5 the preferable form of my improved filing case I do not wish to be limited thereto as there might be various changes made in the details of construction and arrangement of parts described, and hence I desire to avail 10 myself of such changes and modifications as fairly fall within the spirit and scope of the appended claims.

Having described my invention what I claim as new and desire to secure by Letters Patent is:

1. In a device of the class described, a casting comprising top and bottom longitudinal members, transverse partitions interposed between and connecting said members each 20 of which is provided with a plurality of horizontal slots, trays having flanges adapted to seat in said slots, and filing receptacles fitted to slide on said trays, substantially as described.
2. In a device of the class described, top and bottom longitudinal members, transverse partitions having slots arranged in couples and interposed between said members, means for detachably securing said 30 partitions to said members, trays having flanges adapted to seat in said slots, and filing receptacles formed to slide on said trays and provided with hinged lids, substantially as described.
3. In a device of the class described, top and bottom elongated members, slotted partitions arranged in couples and interposed between said members, means for detachably securing said partitions together 40 and to said members, trays the sides of which form downwardly extending flanges adapted to engage the slots, filing receptacles formed to slide on said trays, and lids

hinged to said receptacles and adapted to open automatically when the receptacles are 45 drawn to the open position, substantially as described.

4. In a device of the class described, top and bottom elongated members, slotted partitions arranged in couples and interposed 50 between said members, means for detachably securing said couples together and to said members, trays the sides of which form downwardly extending flanges adapted to engage the slots of said partitions, filing receptacles supported by said trays and designed to slide thereon, and lids hinged to 55 said receptacles by means of rods each of which is provided with an arm which is adapted to engage the end of a partition 60 just before the receptacle is fully withdrawn to open a lid, substantially as described.

5. In a device of the class described, top and bottom elongated rectangular members, horizontally slotted partitions arranged in 65 couples detachably secured to said members and to each other by means of bolts, trays the sides of which form downwardly extending flanges to engage the slots of said partitions, filing receptacles supported by 70 said trays and designed to slide thereon, lids hinged to the top of said receptacles and means for automatically opening and closing the same, card-holding members arranged on the inside of said lids, and number 75 card-holding members arranged on the front of each receptacle, substantially as described.

In testimony whereof I have signed my name to this specification in the presence of 80 two subscribing witnesses.

CHARLES L. GLAFCKE.
